CLAIM

The ornamental design for a mobile device with graphical user interface, as shown and described.

DESCRIPTION

FIG. 1 is a front view of a first image in a sequence of a first embodiment of a mobile device with graphical user interface, showing our new design;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof;

FIG. 6 is a front view of a sixth embodiment thereof;

FIG. 7 is a front view of a seventh embodiment thereof;

FIG. 8 is a front view of an eighth embodiment thereof; and,

FIG. 9 is a front view of a ninth embodiment thereof.

The broken lines illustrate a mobile device, which is the environment of the design and forms no part of the claimed design. The remaining broken lines illustrate a display screen and portions of the graphical user interface that form no part of the claimed design.
